CLAIM

The ornamental design for a mini bow sight, as shown and described.

DESCRIPTION

FIG. 1 is a front elevation view of my design for a mini bow sight that is vertical positioned and depicting a sight aperture having a relatively oval configuration.

FIG. 2 is a back elevation view of the mini bow sight of FIG. 1.

FIG. 3 is a right side view of the mini bow sight of FIG. 1. FIG. 4 is a left side view of the mini bow sight of FIG. 1. FIG. 5 is a top elevation view of the mini bow sight of FIG. 1; FIG. 5 depicts a bow string aperture vertically extending through the mini bow sight.

FIG. 6 is a bottom elevation view of the mini bow sight of FIG. 1; FIG. 6 depicts the bow string aperture of FIG. 5 vertically extending through the mini bow sight.

FIG. 7 is a front elevation view of the mini bow sight of FIG. 1, but with the mini bow sight vertically positioned such that a vertical axis is “tilted” to cause the longitudinal dimension of the oval sight aperture to appear correspondingly reduced. FIG. 8 is back elevation view of the mini bow sight of FIG. 7.

FIG. 9 is a right side elevation view of the mini bow sight of FIG. 7 depicting the vertical “tilt” of the mini bow sight of FIG. 7; and,

FIG. 10 is a left side elevation view of the mini bow sight of FIG. 7 depicting the vertical tilt of the mini bow sight of FIG. 7.
